UNITED STATES PATENT OFFICE.

JOHN A. CRABTREE, OF ERDINGTON, BIRMINGHAM, ENGLAND.

ELECTRIC SWITCH.

Application filed March 20, 1924. Serial No. 700,660.

To all whom it may concern:

Be it known that I, JOHN ASHWORTH CRABTREE, a subject of the King of Great Britain, residing at 170 Orphanage Road, 5 Erdington, Birmingham, England, have invented certain new and useful Improvements in or Relating to Electric Switches, of which the following is a specification.

This invention comprises certain improvements in or relating to electric switches, which improvements are particularly applicable, but not restricted, to switches of the tumbler type. For convenience in description in the following specification, the several axes of the switch mechanism are defined with reference to their altitude, and in the case of a tumbler switch, this altitude has reference to the back of the switch base. The definition of an axis as being located below or above another axis or position thus indicates that the axis in question is respectively nearer to or farther away from the back of the switch base than the point or position in relation to which it is defined. The invention is not, however, strictly limited to these conditions, as obviously precisely the same action might be mounted without a base, and it is, therefore, desired that the present specification be construed accordingly.

According to the present invention, I provide a pivoted operating member which extends downwardly and is adapted to co-operate with the contact member at a position below the pivotal axis of the latter during the whole or a part of the movement, the arrangement being such that the point of co-operation of the operating member with the contact member passes across said pivotal axis beyond the latter in the movements of the switch. The pivotal axis of the contact member may be fixed or movable. In the case of a tumbler switch, the said operating member may constitute a tumbler dolly or a part rigid therewith, or it may constitute a part capable of a limited degree of articulation in relation to the tumbler dolly. The axis of the contact arm may in one embodiment be coupled by a link to a fixed axis so that by virtue of the said link the axis of the contact arm is capable of substantially vertical movement to accommodate the action of the switch mechanism.

In order that this invention may be clearly understood and readily carried into practice, reference may be had to the appended explanatory drawings, in which—

Figure 1 is a sectional elevation of a tumbler switch embodying the present invention.

Figure 2 is a sectional elevation from an aspect at right angles to that of Figure 1 of the switch shown in the figure last mentioned.

Figure 3 is a view similar to Figure 1 showing a modification.

Figure 4 is a similar view to Figure 1 but showing a further modification.

Figure 5 illustrates the modification shown in Figure 4 but with the switch in the "open" position.

Figure 6 is a similar view to Figure 4 but showing a still further modification.

In a convenient embodiment of the present invention as applied to a tumbler switch, the tumbler dolly *a* is mounted in the bridge *b* secured to the base *k* and furnished with a depending operating portion *c* which is pivoted to the contact member *d* at *d*¹. The contact member *d* extends upwardly from its axis *d*¹ of pivotal connection with the depending operating member to a point at which said contact member is pivoted at *e* to a transversely located link *f*. The said link extends to a point at which it is pivoted to move about a fixed axis. At this point it may be mounted upon ears *g* or other bearing members provided upon the bridge *b* or base. Between the axis *e* of connection of the contact member *d* with the link *f* and the axis *j* of the dolly *a*, a compression spring element is incorporated. This may consist of a spring *h* encircling a rod *i* pivoted at the axis *j* of the operating dolly *a* and forked to co-operate with the floating pivot *e* of the link *f*. When, therefore, the axis *d*¹ of pivotal connection of the depending operating portion *c* with the contact arm is displaced in the process of operating the switch it is carried across the plane passing through the axes *j* and *e* of the operating member *a* and contact arm *d*, this action being permitted by the oscillation of the link *f* and contraction of the spring element *h* between the axes *e* and *j*, of the contact arm and tumbler dolly.

Figure 3 illustrates a modification in

which the spring h^1 encircles a rod i^1 which is pivoted to oscillate about the axis j of the tumbler dolly a , the said rod i^1 passing through a perforation in the lug j^1 in the link f .

Figures 4 and 5 illustrate a modification in which the spring h^2 is located between an extension of the link f and an appropriate abutment part of the bridge b .

- 10 In a further modification, as shown in Figure 6, the axis e^1 of the contact arm d may be fixed, and a pin and slot connection may be provided at d^1 between the contact arm and the depending operating member, 15 a compression spring h^3 being incorporated between this pin and the fixed axis e^1 of the contact arm.

A tumbler switch constructed according to the present invention is obviously of the 20 so-called "underslung" type, that is to say, the chord of the arc of movement of the moving contact member is substantially parallel with the back of the switch base.

A tumbler switch, when according to the 25 underslung arrangement as shown and of the one-way type, is such that when it is in position upon a wall with the fixed contacts in the uppermost half of the base, that part of the tumbler dolly which is pressed 30 by the hand has to be displaced downwardly in the process of closing the switch.

The depending part of the operating member being adapted to extend downwardly below the axis of the contact member, 35 which latter is located at level between its axis of connection with the operating member and the axis of the latter, has the result that the arc of movement of the movable contact portion is magnified relatively in 40 relation to the movement of the tumbler dolly so that a measure of rapidity of make and break is thereby obtained.

In the construction defined in the foregoing particular description it will be noted 45 that the arrangement is such that in the event of the spring failing to act, the contact member may be displaced by a partial

or complete positive action into or out of engagement with the fixed contacts.

Having described my invention what I 50 claim and desire to secure by Letters Patent is:—

1. An apparatus of the class described comprising a base, a stationary contact mounted thereon, a movable contact pivotally supported from the base, and an operating lever pivotally mounted on the base and connected directly to the movable contact at a point between the base and the pivot point of the movable contact, whereby 60 to positively move the movable contact into and out of contact with the stationary contact.

2. An apparatus of the class described comprising a base, a stationary contact 65 mounted thereon, an operating lever pivotally mounted on the base, a link pivotally connected to the base, and a movable contact member pivotally carried by the same adjacent to the free end thereof, said operating lever being positively connected to the movable contact member at a point between the base and the pivot point of the movable contact.

3. An apparatus of the class described 75 comprising a base, a stationary contact mounted thereon, a link pivotally carried by the base, a movable contact pivotally carried by the link adjacent to the free end thereof, an operating lever pivotally mounted on the 80 base and positively connected to the movable contact at a point between the base and the pivot point of the movable contact, and means positioned between the base and the free end of the link to urge the movable contact into either of two extreme positions when said contact is moved by the lever to a point to one side or the other of the center line through the pivot points of the operating lever and its point of connection with the pivoted contact.

In testimony whereof I hereunto affix my signature.

J. A. CRABTREE.
